DEVICE FOR ADJUSTING THE PITCH OF AIR PROPELLERS

Robert Prause, Augsburg, Germany; vested in
the Alien Property CustodianApplication October 22, 1940, Serial No. 362,279
In Germany June 10, 1938

1 Claim. (Cl. 170—163)

1

This invention relates to a propeller adjustment device.

Certain devices for the adjustment of the pitch of air propellers while in operation are known in which the blade adjustment is carried out by means of a bushing or sleeve mounted to slide on the propeller shaft. The sliding operation of said bushing or sleeve is effected by means of an adjusting lever or traverse which surrounds the bushing and at one end is mounted to swing on a stationary point of the aeroplane, the other end being connected by a simple link with an adjustable system of rods leading to the pilot's seat. The sliding motion received by the sliding bushing is transferred to the base of the propeller blades, which are turnably mounted, by means of jointed levers. Although this known device enjoys the advantage of great simplicity as compared with other designs of blade adjustment, it has not proven useful in actual practice. It was found that the suspension arrangement which allows the adjustment traverse surrounding the sliding bushing to swing around one axis only, or around two parallel axes, showed considerable wear and tear, especially at the sliding bushing, after only a few flying hours.

It is an important object of the present invention to provide means in the adjustment device for avoiding such premature wear. In the course of the investigations leading to the present invention it has been found that this defect of the known device is mostly due to the fact that the propeller shaft and the axis for the swing adjustment of the traverse while in operation deviate imperceptibly from their original position at right angles to each other. Such deviation is brought about by certain forces during the flight. The relatively rigid connection of the adjustment traverse on one side and the play of the parts belonging to the adjustment device on the other side tend to cause a sort of wobbling motion of the traverse ring, or of the sliding bushing, causing the latter to deteriorate and to wear out rapidly, since the adjustment traverse owing to its rigid connection cannot give way to the oscillating movement. Moreover, the sliding motion of the adjustment sleeve causes an edgewise pressure stress which, in cooperation with the wobbling motion, tends to wear out the sliding bushing.

Therefore, the present invention has for its object to provide a construction of a propeller adjusting device which permits wobbling motion of the parts without any substantial wear. With these and further objects in view, as may be

2

come apparent from a consideration of the annexed drawings and the following description, the invention consists not only in the structures herein pointed out and illustrated by the drawings, but includes further structures coming within the scope of the claim.

The character of the invention, however, may be best understood by reference to certain of its structural forms, as illustrated by the accompanying drawings in which:

Fig. 1 shows a schematic, perspective view of the essential parts of an adjustment device having the invention applied thereto.

Fig. 2 is a side elevation, partly in section, of the same adjustment device.

Fig. 3 is a plan view, partly in section, on line III—III of Fig. 2.

Fig. 4 is a section according to line IV—IV of Fig. 2.

Fig. 5 is a section similar to Fig. 4, but showing another design of the gimbal mounting of the adjustment device.

As here shown, I provide means between the stationary points for the suspension of the device and the sliding bushing or sleeve for permitting a Cardan motion, or relative swinging of the parts around two axes at right angles to each other. The traverse lever for adjusting the sliding bushing is suitably designed as a ring surrounding the bushing. Said ring at one end is mounted at a stationary point of the aeroplane, preferably by means of a link or swing member, so as to move around two perpendicular axes, while at its other end the adjustment spindle is connected, movable, also around two perpendicular axes, by means of the spindle nut. The annular traverse lever which surrounds the sliding bushing and the propeller shaft is connected with the sleeve effecting the blade adjustment by means of a ball bearing which preferably is of a type to receive axial forces. The traverse ring is swingably connected with the outer ring, or with the supporting ring for the ball bearing, by means of trunnions.

By arranging the component parts or elements, as above described, which make possible a gimbal movement of the adjustment sleeve, great improvement in the stress conditions of the adjustment device has been obtained and, as a consequence, the number of flying hours could be considerably increased. Preferably, and as here shown, I may obtain a further improvement of the stress conditions by manufacturing the adjustment sleeve and/or a sliding bushing mounted on the propeller shaft from synthetic

material, especially synthetic resin with textile inserts or admixtures. This material may consist of various kinds of synthetic compressed material such as phenol-aldehyde condensation products which are known as "Bakelite." Also resin impregnated fabrics, hard wood and hard paper of all sorts as well as any pressing material from paper and textiles in layers in non-laminated form may be used after having been treated with a suitable binding substance. The sliding bushing mounted on the propeller shaft can be made of such synthetic material, while the sleeve moving thereon can be made of metal. By manufacturing the bushing and/or sleeve from any of the synthetic materials mentioned, a longer life of the device is obtained than would be the case if it would be manufactured exclusively from metal or metal alloys. Even if metal alloys of the highest abrasion resistance are used in the manufacture of said bushing and sleeve, undesirable quick wear have been found to be unavoidable. Applying the experience so far made with slide bearings of artificial material, it was surprising to find out that by using synthetic material in the device, according to the invention, the dangerous stresses at the edges of the sleeve could be met.

Referring now to the drawings in greater detail, and first to Figs. 1 to 4, it will be seen that the propeller blades 1 and 2 of a two blade propeller are turnably mounted in the propeller hub 3. The hub 3 is coupled with a hollow propeller shaft 4 by means of two mutually engaged toothed portions indicated at 5, both parts being held together by a threaded member 6. The propeller shaft 4 at its other end is shaped to fit the different motor connections and is connected with the motor shaft by bolts 7. An anti-friction bushing or sleeve 8 consisting of synthetic resin on a phenol-aldehyde basis with textile admixtures is fastened on the hollow shaft 4 by means of screw bolts 9, for reception of an adjustment sleeve 10 mounted to slide on the bushing 8, and provided with eyelets 11 which have the guide members 12 jointed to them for connection with adjustment levers 13 which are rigidly screwed to the base of the propeller blades by means of their female thread so that any swinging of the levers 13 will also cause the propeller blades 1 and 2 to be turned correspondingly. The adjustment sleeve 10 is surrounded by the ring-shaped adjustment traverse lever 14 which at its extreme opposite ends I and II is connected by means of a Cardan or universal joint to connecting members which in turn are suspended at stationary points of the aeroplane. The connection at II is adjustable in such a way that the traverse ring during the adjustment can be swung around the point I. The suspension of the traverse ring 14 at I is movable but not adjustable. The traverse ring 14 is connected to a fork-shaped end 17 of a guide member or rod 15 by means of a self-aligning ball bearing 19 and a trunnion 18 as shown in Figs. 3 and 4. The other end of the rod 15 is connected at 16 to a fixed bracket which is rigidly attached to some part of the aeroplane such as the motor for propelling the plane. Said bearing 19 is mounted in the eye 20 of the traverse ring 14 so that the traverse ring can be turned around two perpendicular axes with respect to the guide member 15. The traverse ring 14 can be swung around the suspension at I by means of the adjustment spindle 21 connected at II, thus producing the adjusting motion. A self-aligning ball bearing

22 at the right-hand end, Fig. 3, of the spindle 21 permits rotation thereof as well as swinging through a certain angle, but prevents axial movement of the spindle which carries a nut 23 mounted to swing in all directions, with respect to the traverse ring 14, at II, by means of a self-aligning ball bearing 24. The nut 23 is prevented from turning by an arm 25 and a bolt 26. The nut 23 is also prevented from sliding with relation to the traverse ring 14 by means of the threaded rings 27 and 28, the first ring being screwed together with the traverse ring 14 and serving as a frame for the ball bearing 24, while the second ring is mounted on the other side of the ball bearing 24 and screwed together with the nut 23. The free end of the spindle 21 is provided with a safety-and-stop ring 29. Displaced by 90° in relation to the suspension points I and II, the traverse ring 14 carries trunnions 30 and 31 (Fig. 4), between which rests the supporting ring 32 for the ball bearing 33. The inner ring 34 of the bearing 33 is mounted on the adjustment sleeve 10, being forced against the stop 36 of the adjustment ring 10 by means of a threaded ring 35. Another threaded ring 37 which is screwed into the supporting ring 32 helps to hold the outer ring of the ball bearing within the supporting ring. A key 38 engaging in a suitably dimensioned slot of the sliding bushing 8 prevents the adjustment sleeve 10 from turning with relation to the bushing 8.

Instead of the Cardan-like connection by provision of self-aligning ball bearings between the traverse ring 14 and the guide member 15 as well as the spindle 21, the traverse ring can also be connected Cardan-like or gimbal-fashion with the adjustment sleeve or with the supporting ring 32 of the ball bearing 33 by means of an auxiliary ring 32' (Fig. 5). This ring 32' can be swung around the trunnions 30 and 31, while the supporting ring 32 can be swung perpendicularly thereto around the trunnions 30' and 31' of the ring 32'.

When in operation the propeller revolves around the propeller or motor axis III-III jointly with the hollow shaft 4, the anti-friction bushing 8 mounted thereon, the adjustment sleeve 10 and the inner ring 34 of the ball bearing 33, with relation to the outer ring of the ball bearing and the remaining parts of the adjustment traverse. The position or pitch of the propeller blades is dependent upon the axial position of the adjustment sleeve 10, and consequently upon the position of the nut 23 on the spindle 21 which can be turned in the self-aligning ball bearing 22 by means of a Cardan drive 40, as indicated by the broken line on Fig. 3. Rotation of the spindle 21 causes the nut 23 to be moved axially and, since the latter is fixed immovably in the traverse ring 14, it is bound to take along the traverse ring swinging same around the trunnion 18 of the suspension point I. Through this swing movement the adjustment sleeve 10 is moved on the bushing 8 by means of the ball bearing 33 adapted to carry an axial load. This movement is transferred by way of the guide members 12 to the adjusting levers 13 which in turn take along the propeller blades and cause them to turn in their bearings.

Owing to the Cardan-like or gimbal mounting of the traverse ring by means of self-aligning ball bearings, all parts of the adjustment device can follow up any possible "skewing" which might emanate from the forces taking effect dur-

ing the flight, so that premature wear and tear of the adjustment sleeve 10 or the bushing 8, will be largely avoided. By manufacturing the sliding bushing 8 from synthetic material it is possible to preclude any appreciable wear even in continuous operation. It is contemplated within the purview of this invention that the antifriction bushing 8 as well as the adjustment sleeve 10 or either of said parts may be made of resin-impregnated fabric or any similar material.

The adjustment of the propeller blades is accomplished, as described above, by turning the threaded spindle 21 by means of the indicated Cardan drive member 40, which can be done manually, mechanically or electrically. In place of an electric drive with rotating screw spindle a hydraulic drive can also be employed.

The present invention has been described in detail with reference to specific embodiments. It is to be understood, however, that the invention is not limited by such specific reference but is broader in scope and capable of other embodiments than those specifically described and illustrated in the drawings.

I claim:

In an adjustable pitch propeller for aircraft, the combination of a propeller hub; propeller blades mounted in said hub to be adjustably rotated about their longitudinal axes; a propeller shaft on which said hub is rigidly mounted; a sleeve mounted coaxially and slidably on said

shaft; means operatively connecting said sleeve with said blades and adapted to rotate said blades upon axial movement of said sleeve; a fixed bracket; a link pivoted at one end on a horizontal pivot pin in said bracket, and having a fork at its other end; a traverse ring disposed about said shaft; a ball-bearing having its outer race pivoted in said traverse ring for movement about an axis transverse to the axis of the shaft, and its inner ring fixed about said sleeve; a boss on said ring; a self-adjusting ball bearing in said boss; a trunnion in the fork of the link, on which said ball bearing is mounted, the link and ring being so connected by the ball bearing that the ring is capable of movement about two axes perpendicular to the axis of the link; a second fixed bracket; a second self-adjusting ball bearing mounted in said second fixed bracket; a rotatable, threaded spindle journaled in said second ball bearing; means for rotating said spindle; a nut threaded on said spindle; and a third self-adjusting ball-bearing mounted in said traverse ring diametrically opposite to the said boss and in which said nut is carried, the spindle and traverse ring being so related that when the spindle is rotated the traverse ring is moved about one of the axes perpendicular to the axis of the link, to slide said sleeve axially of the propeller shaft, cause the link to pivot about the first fixed bracket, and cause the spindle to pivot about the second fixed bracket.

ROBERT PRAUSE.
